Inventor

UNITED STATES PATENT OFFICE.

SAMUEL G. CABELL, OF WASHINGTON, DISTRICT OF COLUMBIA.

MEANS FOR PREVENTING INCRUSTATION IN STEAM-BOILERS.

SPECIFICATION forming part of Letters Patent No. 409,136, dated August 13, 1889.

Application filed June 25, 1889. Serial No. 315,567. (No model.)

To all whom it may concern:

Be it known that I, SAMUEL G. CABELL, a citizen of the United States, residing at Washington, in the District of Columbia, have invented certain new and useful Improvements in Electro-Magnets; and I do hereby declare that the following is a full, clear, and exact description of the invention, such as will enable others skilled in the art to which it applies to make and use the same.

My invention relates especially to magnets for preventing the incrustation or formation of earthy deposits in steam-boilers, and for other purposes.

15 The invention consists, essentially, in a hollow vessel or core and a plurality of magnetic points or projections extending into, and across the space within the walls.

20 In the drawings I have illustrated a convenient form of apparatus involving my invention for purifying feed-water and other liquids, in which—

25 Figure 1 is a central vertical section showing an apparatus involving my invention arranged in an upright position. Fig. 2 is a similar section arranged horizontally. Fig. 3 is a plan of one of the rings and its inwardly-projecting magnetic or pole points, and Fig. 4 is a sectional detail.

30 A is a tubular vessel or conduit of any suitable material, and a a' are respectively inlet and outlet passages.

35 B B are rings of magnetic material, preferably of soft or malleable iron, each armed with a series of inward magnetic projections or points b b. These points may extend to or beyond the center and in any direction across the space within the rings, as may be desired. The rings may be separated from each other 40 by interposed rings of non-magnetic material, as shown by heavy lines, Fig. 2, and they may be severed diametrically and have non-magnetic pieces interposed and the parts doweled together, as shown at b' b', when expedient or desirable. The conduit or vessel may be of any desired length and may be arranged in any suitable direction.

45 In Fig. 1 I have shown the vessel in an upright position and made up of a plurality of sections of cylinder and having the inlet near the bottom, the outlet at the top, and a settling-chamber α^2 below the inlet, with a drain-cock leading therefrom.

For convenience of manufacture I provide

flanges α^3 α^3 at the extremities of the tube-sections, by means of which they may be bolted together. They also serve as shoulders, against which the coils of the helix may be supported.

55 A ring of brass or other non-magnetic material, or a neck-like section, as D, is by preference interposed between the flanged tube-sections to divide the conduit into separate magnetic sections. The inward projections may be hard-steel permanent magnets, or 60 they may be of soft iron energized by a magnetic helix. The necessary condition of the points is that they be magnetic.

65 I have shown around and upon the conduit or vessel a helix C, of insulated wire, in circuit with a source of electricity for periodically charging the hard-steel points to make them magnetic, or for constantly energizing such points, whether steel or iron.

70 In use as a feed-water purifier the vessel A is arranged upon a suitable support between the water-supply and the mud-drum of a steam-boiler, and connections made with inlet and outlet passages, so as to cause the feed-water to pass through said vessel to the 75 circulation in the boiler.

80 Obviously, one of the heads or ends of the vessel may be omitted and the device suspended by a suitable hollow neck in a boiler or other vessel for affecting and purifying 85 the contents with magnetism.

85 Having described my invention and the manner of applying the same, what I claim is—

1. The combination of a hollow vessel or 90 conduit made up of a plurality of sections having interposed non-magnetic rings and a plurality of magnetic points or projections extending into and across the space within the walls of said vessel, substantially as described.

95 2. The combination of a hollow vessel and a plurality of rings, each carrying a plurality of magnetic points, extending into and across the space within the rings, substantially as described.

100 In testimony whereof I affix my signature in the presence of two witnesses.

SAMUEL G. CABELL.
